BY

UNITED STATES PATENT OFFICE.

WILLIAM U. GRIFFITHS, OF PHILADELPHIA, PENNSYLVANIA.

VALVE-ACTUATING MECHANISM FOR WATER-CLOSET APPARATUS.

1,149,258.

Specification of Letters Patent. Patented Aug. 10, 1915.

Application filed September 3, 1913. Serial No. 787,842.

To all whom it may concern:

Be it known that I, WILLIAM U. GRIFFITHS, a citizen of the United States, and a resident of Philadelphia, in the county of Philadelphia and State of Pennsylvania, have invented certain new and useful Improvements in Valve-Actuating Mechanism for Water-Closet Apparatus, of which the following is a specification.

10 My invention relates to improvements in flush tanks for flushing water closet hoppers and the like, and has for its object to provide an improved means for positively and effectively controlling the operation of the discharge valve of the flush tank.

15 A further object of my invention is to provide an apparatus which is simple in construction, effective in operation and particularly adapted for positive action.

20 In the accompanying drawing I have illustrated one form of a convenient embodiment of my invention, but it will be understood that changes in the details of construction may be made within the scope of the claim 25 without departing from the same.

25 In the drawing, I have shown a water closet apparatus embodying my invention, the flush tank and a portion of the adjacent mechanism being shown in vertical longitudinal section, while other adjuncts of the mechanism are shown in side elevation.

30 Referring to the drawing, 1 designates a water closet hopper or bowl, and 2 a valve mechanism for controlling the flow of water from a suitable source of supply through a pipe 3 to the flush tank 4. The valve mechanism as here shown is controlled by means of a rod 5 slidably mounted in a suitable support or bearing and adapted to be operated by the means of the movement of the seat 6 which it will be understood is pivoted at 7, and when depressed strikes the end of the rod 5 and causes the valve to be opened to supply water to the tank 4. The seat 6 is normally held in raised position, as shown in the drawings, by means of a weighted arm or lever 8, which, as will be readily apparent, is so arranged as to maintain the seat 6 in elevated position as shown. 9 designates an arm suitably fixed in any desired manner to the seat 6 and depending therefrom so as to normally extend downwardly into the mouth of the bowl 1 where it is adapted, when the seat is depressed, to contact with the end of the rod 10 which is

cured in the flush delivery pipe 12. The opposite end of the rod 10 is secured at 13 to a pair of links 14 which, together with the links 15, form a toggle mechanism connected at one side to a plug 16 and at the opposite side to a valve operating rod 17. This latter extends within the pipe 18 as a continuation of the pipe 12, and enters the flush tank 4 by way of the overflow pipe 19, where there is a U-shaped bend which permits the end of said pipe to pass downwardly within the flush tank 4 and through the discharge port 20. The lower end of the rod 17 passes through a hole in a cross piece 17^a by which it is held and guided in its movements. It will be noted that the pipe 18 is preferably provided with an extension 21 for the purpose of receiving the valve member 22 which is fixed to the end of the rod 17 and is adapted to close the opening 20 at certain times.

Particular attention is directed to the novel toggle mechanism interposed between the valve rod and the operating rod controlled by the movement of the seat 6, since this is an important feature of my invention and serves as a positive means to control the movement of the valve 22 and also magnifies the movement of the rod 10 in order to insure the opening of the valve 22 at the desired time.

The operation may be described as follows: When the seat 6 is depressed, it contacts with the upper end of the rod 5 so that the valve or valves in the mechanism 2 are opened to permit water to flow into the tank 4 and fill the same. Simultaneous with this operation, the arm 9 has been brought into contact with the rod 10, thereby shifting the latter, and through the toggle connections above described, raise the rod 17, and consequently close the valve 22 so that the water entering the flush tank 4 may not escape until the said tank is filled or partially filled. As soon as the seat 6 is released, the weight 8 causes it to return to the position shown in the drawing, thereby closing the valve mechanism 2, to cut off the supply of water, and as the rod 10 is relieved from pressure on the arm 9, the weight of the rod 17 with its adjuncts causes the parts to lower, thus opening the valve 22 and allowing the tank 4 to discharge in the usual manner.

I claim:

Water closet apparatus comprising a water closet bowl having a hollow arm project-

ing from the rear side thereof, a flush tank having a port therein and also having an open-ended pipe therein terminating at a point a distance below the upper edge of the said tank, a pipe secured to the said hollow arm and extended upwardly therefrom and having connection with the lower side of the said tank in alinement with the pipe therein, toggle links situated in the said horizontal arm at the rear end thereof and having pivotal connection therewith, a rod having connection at its lower end to the upper end of the said toggle links, which rod extends upwardly through the said pipes into the flush tank and being provided with a valve for closing and opening the port in the said

tank, a second rod having connection with the said toggle links and extending in a horizontal direction through the said arm into the said water closet bowl, and means 20 for actuating the said last mentioned rod for operating the said toggle links to cause the said valve to be closed and opened.

In testimony that I claim the foregoing as my invention, I have hereunto signed my 25 name this first day of September, A. D. 1913.

WILLIAM U. GRIFFITHS.
